D. Anthony Usina
his Attorney.

UNITED STATES PATENT OFFICE.

PERCY J. HINDMARSH, OF LINCOLN, NEBRASKA, ASSIGNOR TO THE AMERICAN STEEL
AND WIRE COMPANY OF NEW JERSEY, A CORPORATION OF NEW JERSEY.

FENCEPOST.

Application filed October 3, 1924. Serial No. 741,421.

This invention relates to fence posts and more particularly to rolled metal fence posts, and has for its object the provision of an improved form of fence post of T-shaped cross section adapted to provide a greater bearing surface for the wire than with posts heretofore provided.

Another object is to provide notches or depressions along the longitudinal edges of the flanges of the post for holding the fence securing clips against longitudinal movement.

A further object is to provide a post having the novel construction, design and combination of parts hereinafter described and illustrated in the accompanying drawings.

In the drawings—

Figure 1 is a front elevation of a post constructed in accordance with this invention.

Figure 2 is a transverse sectional view on the line II—II of Figure 1.

Figure 3 is a fragmentary front elevation showing a slightly modified form of post.

Referring more particularly to the drawings, the fence post as shown is substantially T-shaped in cross section and has the general characteristics of a rail in that it comprises a web or stem portion 2, flanges 30 or back 3 and a head or bulb-like enlargement 4 along the longitudinal edge of the web opposite the flanges 3. The enlargement 4 serves to strengthen or stiffen the post and prevents flexing thereof during the driving of the post or during use.

The flanges or back 3 are provided with a flat outer or fence engaging face and are of a materially greater width than the depth of the web or stem 2. The extra wide flanges 40 or back 3 serves to provide a maximum bearing surface for the fencing wire and also provides ample surface in the ground to give stability without the use of anchor plates or the like.

It will be understood, however, if desired, anchor plates of any suitable construction (for example the anchor 6 shown in Figure 1) may be provided to provide further stability in the ground.

The fencing, designated by the numeral 7, is adapted to be held in position on posts of this class by clips 8, which have their ends bent back to engage around the edges of the flanges or back 3. In order to pre-

vent the fencing 7 and clips 8 from moving longitudinally relative to the posts, I provide a continuous series of undulations forming notches or depressions 9 in the longitudinal edge faces of the flanges or back 3, into which the clips 8 are adapted to be fitted, and since the clips 8 are of such size that they will fit snugly against the lowermost portion of the depressions they cannot move vertically.

In Figure 1 I have shown the notches 9 in the opposite side edges of the flanges or back 3 in line with each other. However, if desired, the notches may be staggered as shown in Figure 3.

It will be understood that the use of these posts is not limited to woven wire fencing, as shown in the drawings, but may also be used to support plain or barbed wire, netting or any other kind of fencing, as desired.

The principal advantage of posts constructed in accordance with this invention is that they afford a maximum of bearing surface for the fencing, and that the notches are so positioned that they will hold the clips 8 regardless of whether knots or other heavy portions of the fencing are against the face of the posts.

Heretofore posts have been made with projections on the wire engaging face of the posts, which projections were adapted to hold the fencing and clips against longitudinal movement relative to the posts. However, if a barb on barbed wire or knot in woven fencing was positioned so as to engage the face of the posts, neither the fencing nor clips would seat in the notches and, therefore, vertical movement was not prevented.

While I have shown and described specific embodiments of my invention, I do not wish to be limited thereto, since various modifications may be made without departing from the scope of my invention as defined in the appended claims.

I claim—

1. A rolled metallic fence post consisting of a T-bar having relatively broad flat flanges or back, said back having a continuous series of undulations forming notches along the longitudinal edge faces thereof.

2. A rolled metallic fence post consisting of a T-bar having a stem portion enlarged

along its free longitudinal edge to form a bulb adapted to strengthen and stiffen said post, and having its flanges or back of materially greater width than the depth of 5 said stem, said flanges or back portion having a flat outer face and being provided with a continuous series of undulations along the full length of its longitudinal edges, the undulations of said edges forming notches or 10 depressions to receive fence retaining clips.

3. A rolled metallic fence post consisting of a T-bar having its flanges or back of materially greater width than the depth of its stem, and said flanges or back portion having a flat outer face and being provided 15 with a continuous series of undulations along the full length of its longitudinal edges, the undulations of said edges forming

notches or depressions to receive fence retaining clips. 20

4. A rolled metallic fence post consisting of a T-bar having its flanges or back of materially greater width than the depth of its stem, said flanges or back portion having a flat outer face and being provided with a 25 continuous series of undulations along the full length of its longitudinal edges, said undulations consisting of short curved concave portions connected by long curved convex portions, and said concave portions forming notches or seats to receive and hold fence retaining clips against vertical movement.

In testimony whereof I have hereunto set my hand.

PERCY J. HINDMARSH.
